(57) **CLAIM**

We claim the ornamental design for a receiver enclosure, as shown.

DESCRIPTION

FIG. 1 is a front, top, right side isometric view of the receiver enclosure;

FIG. 2 is a top view thereof;

FIG. 3 is a front view thereof;

FIG. 4 is a left side view thereof;

FIG. 5 is a right side view thereof;

FIG. 6 is a back view thereof;

FIG. 7 is a back, bottom, left side isometric view thereof; and, FIG. 8 is a bottom view thereof.

The broken lines shown throughout the views, which are immediately adjacent to the shaded areas and define unshaded regions, including the space between the top and bottom halves which is defined by broken lines on three sides, represent the bounds of the claimed design. All other broken lines are directed to environment and are for illustrative purposes only; the broken lines form no part of the claimed design.
